P. H. DAUB

SAFETY DEVICE

Filed June 18, 1925

Philip H. Daub, Inventor

284

Attorney

UNITED STATES PATENT OFFICE.

PHILIP H. DAUB, OF HELENA, OHIO.

SAFETY DEVICE.

Application filed June 18, 1925. Serial No. 38,097.

To all whom it may concern:

Be it known that I, PHILIP H. DAUB, a citizen of the United States, residing at Helena, in the county of Sandusky and State of Ohio, have invented certain new and useful Improvements in Safety Devices, of which the following is a specification.

This invention relates to mechanical devices for operating a safety gate or signal or signal lights and the like.

An object of this invention is to provide a mechanical device which will automatically, by the passing of a train in one direction, operate a railway safety device or gate or signal or signal lights or any kind of signal or gates at railroad crossings, or where main market or other roads cross the railroads, and which will be inoperative when the train is moving in the opposite direction.

It is a further object of this invention to provide a device on the outside of the rail and to provide a device in which a broken flange or any imperfection will not interfere with the operation of the device or injure the train by contacting the device.

A further object of this invention is to provide a device of this character which is positive in operation, which is of simple construction, which is easily and quickly installed, and which may be installed without any change in the rail structure, and which may be manufactured at a minimum cost.

With the foregoing and other objects in view, I have invented the device shown in the accompanying drawings, in which:

Figure 1 is a top plan view of a railroad provided with my device.

Figure 2 is a side elevation in normal condition.

Figure 2^a is a like view to Figure 2 showing the operation upon a car wheel passing in one direction.

Figure 3 is a top plan view of the base plate.

Figure 4 is a side elevation of the link buffer separated.

Figure 5 is a top plan view of the showing in Figure 4.

Figure 6 is a detail.

Like reference characters indicate like parts throughout the several views and in the specification in which there is provided a base plate 2 adapted to be inserted be-

neath the rail 3 of the track. The plate 2 carries rollers 4. Slidably mounted upon each of the rollers 4 by means of slots 5 are link members 6 and 7, mounted to each other at 8 by a tongue 9 and yoke bearing 10 and a pivot pin 11. Carried at the distal end of the link 7 is a pulley 12, and interconnecting the distal end of the link 6 with a tie such as 13 is a helical compression spring 14. Carried by the plate 2 is a pulley 15 and suitably spaced upon the ties of the track are pulleys 16. Passing over the pulleys 16 and partially around the pulley 15 and partially around the pulley 12 is a cable 17, the cable 17 being connected with an adjustable eye-bolt 18 mounted in a tie 19. In assembling, the cable 17 is suitably adjusted by means of the bolt 18, so that, by a predetermined pressure the device normally rests as in Figure 2. That is to say, the joined portions of the links 6 and 7 are slightly upstanding above the surface of the rail 3. Upon the passage of a train to the right, as shown in Figure 2^a, the wheel 20 of the car contacts the link 6, and by reason of the angularity of the positioning of the members 6 and 7, pushes against the member 7 to slide upon the roller 4 and push against the pulley 12, causing a tightening of the cable 17 and the actuation of any suitable signalling or gate-closing or other safety device, the cable 17 being suitably connected with any desired safety device or appliance, or with a means for actuating such a device from a remote position. If the train should be passing toward the left, as shown in Figure 2^a, then the wheel 20 would contact the link 7, which would push against the link 6 and against the spring 14 and would have no action upon the cable 17, so that it would not operate the safety device. The links 6 and 7 are preferably mounted upon the outside of the rails 3 and adapted to be engaged by the rim of the wheel and not by the flange of the car wheel.

It is obvious that by the use of this device, the rail is not weakened in any manner, as no holes are put through the rail, as all the support is carried by the shoe or plate 2. Furthermore, by this structure, a breakage of the flange of the car wheel will in no manner militate against the operation of the device, nor will the contact with a

broken part of a flange endanger the operation of the train.

It is obvious that the above device may be placed at suitable places along the railway and in reverse relation to each other, as, for instance, one upon each side of a cross road bed, one of these two working in a reverse direction to that of the other, so that upon the passage of the train in one direction, one of the devices is operated to control the safety device, whereas upon the passage of a train in the reverse direction, the other is operated to control the safety device.

It is further obvious that this device, being purely mechanical in its operation and of simplified construction, dispenses with complicated devices such as hydraulic, water power, and the like. It is further obvious that by this cable means, the device can be operated at a considerable distance from the signal or gate and that the cable can be run a great distance so that the device can be fastened on the rail a great distance from the road crossings.

It is further obvious that when used with counter-balance gates, the length of the links 6 and 7 may be such that no further control means need be had, in that the gate can be held entirely open by this device until the full train has passed over, which cannot be had with the usual trip devices.

Claims—

1. A safety attachment for a railway, including slidably mounted ramps, a cable connected with one of the ramps, and means for mounting the ramps to move the cable in a single direction.

2. In combination with a railway rail, a pair of bar-like members provided with longitudinal slots pivotally mounted relative to each other, means adapted to engage the slots, a spring mounted at the terminal of one of the bar-like members, and controlling means adapted to be actuated by the other bar-like member.

3. In a railway safety device, a member adapted to be mounted at the side of a rail, the member including a pair of articulated wheel ramps, the ramps slidably mounted, a spring engaging one of the ramp

members and the other ramp adapted to actuate the safety device.

4. In combination with a railway rail, a pair of bar-like members provided with longitudinal slots pivotally mounted relative to each other, means adapted to engage the slots, a spring mounted at the terminal of one of the bar-like members and a cable adapted to be actuated by the other bar-like member.

5. In combination with a railway rail a pair of members each held at an acute angle relative to the rail, the members pivoted together, a spring at the terminal of one of the members, a pulley carried by the terminal of the other member, and means adapted to cooperate with the pulley for operating a safety device.

6. In combination, a flexed member adapted to be carried by the side of the rail and to be contacted by a wheel passing over the rail, a pulley carried by one of the members, a cable and means for affixing the cable to a tie, the pulley adapted to movingly engage the cable.

7. In combination in a railway safety device, a cable, means for adjustably fixing the cable to a tie, pulleys associated with the railway and a member in the path of a car wheel adapted upon a predetermined contact of the car wheel to press against the cable.

8. In combination with a railway, a plate adapted to be carried beneath the rail, a pair of link members pivoted together and slidably mounted to the plate member, the link members in the path of a wheel passing over the rail, and means interconnected with the link members for actuating a safety device.

9. In combination, a flexed member provided with longitudinal slots, a portion of the flexed member in the path of a wheel passing over the rail, means interconnected with the flexed member for operating a safety device upon a predetermined contact of the wheel and flanged roller members mounted within the slots.

In testimony whereof I affix my signature.

PHILIP H. DAUB.
